Primary Examiner—Robin V. Taylor

[57] CLAIM

The ornamental design for a hose and nozzle cover, as shown and described.

DESCRIPTION

FIG. 1 is an exploded left side elevational view of the hose and nozzle cover of the present invention, the right side elevational view being a mirror image of thereof;

FIG. 2 is an exploded front elevational view of the hose and nozzle cover of FIG. 1;

FIG. 3 is an exploded back elevational view of the hose and nozzle cover of FIG. 1;

FIG. 4 is an exploded top plan view of the hose and nozzle cover of FIG. 1; and,

FIG. 5 is an exploded bottom plan view of the hose and nozzle cover of FIG. 1.

The claimed design is shown fragmented in FIGS. 1, 4 and 5 to indicate indeterminate length.
